REFRIGERATING APPARATUS

Lawrence A. Philipp, Detroit, Mich., assignor to
 Nash-Kelvinator Corporation, Detroit, Mich., a
 corporation of Maryland

Original application August 8, 1940, Serial No.
 351,834. Divided and this application June 23,
 1941, Serial No. 399,313

1 Claim. (CL 62—8)

This invention relates to refrigerating apparatus, and more particularly to refrigerating apparatus of the multiple temperature type.

The present application is a division of my co-pending application, Serial No. 351,834, filed August 8, 1940, for Refrigerating apparatus.

Another object of my invention is to provide an improved refrigerating system which includes heat absorbing means having the different portions thereof separated by a fixed restriction which provides for the operation of one portion at a higher pressure and temperature than the other portion, and to provide for the flow of liquid refrigerant to the heat absorbing means by a small diameter tube, and to pass the evaporated refrigerant in thermal heat exchange with said small diameter tube so as to pre-cool the liquid refrigerant in the cabinet.

Further objects and advantages of the present invention will be apparent from the following description, reference being had to the accompanying drawing, wherein a preferred form of the present invention is clearly shown.

In the drawing:

The figure in the drawing is a diagrammatic illustration of a refrigerating system illustrating features of my invention.

Referring to the drawing, my improved refrigerating system includes a motor compressor unit 24, condenser 26, high temperature heat absorbing sections 28 and 30, low temperature refrigerating sections 32, 34, 36 and 38, and an accumulator 40. Evaporated refrigerant is withdrawn from the accumulator 40 through a vapor return conduit 42 whence it passes to the motor compressor unit 24 wherein it is compressed and from which it is delivered through conduit 46 to condenser 26. In the condenser it is liquefied and from which it is delivered to heat absorbing section 28 through a small diameter tube 48 after first passing through a strainer device 50. The refrigerant passes from the section 28 through conduit 52 to the section 30. Before passing to the section 32 from section 30, the refrigerant must pass through a fixed restriction, or small diameter tube 56. This reduces the pressure of refrigerant flowing to the sections 32, 34, 36 and 38 so as to maintain a higher temperature in the

sections 28 and 30 than in sections 32, 34, 36 and 38. This system is of the non-flooded type wherein droplets of liquid refrigerant are passed into the heat absorbing sections, but due to the absorption of heat very little, if any, liquid refrigerant passes into the accumulator 40. Thus, the refrigerant passing through conduit 42 is gaseous refrigerant and, as disclosed, I have arranged the conduit 42 in thermal heat exchange relation with the small diameter tube 48 so as to cool the liquid refrigerant passing through the tube 48. These two conduits may be secured together by solder if desired.

The above refrigerating system may be installed in a cabinet of the type disclosed in the aforementioned application Serial No. 351,834, of which the present application is a division. The system may also be operated and controlled as disclosed in said co-pending application.

Although only a preferred form of the invention has been illustrated, and that form described in detail, it will be apparent to those skilled in the art that various modifications may be made therein without departing from the spirit of the invention or from the scope of the appended claim.

I claim:

A refrigerating system comprising, a condensing mechanism, high temperature heat absorbing means and low temperature heat absorbing means adapted to receive liquefied refrigerant from said mechanism, a small diameter tube for progressively reducing the pressure of said liquid flowing from said mechanism to said high temperature means, refrigerant flow control means between said high temperature means and said low temperature means to maintain one means at a higher pressure and temperature than the other, a vapor conduit for conducting vaporized refrigerant from said low temperature means to said mechanism and having a portion thereof thermally united to said small diameter tube to precool the liquid flowing through said tube, and a refrigerant accumulator connecting the inlet of said conduit with the outlet of said low temperature means.

LAWRENCE A. PHILIPP.
